SOAP PREPARATION

John Ross, Ramsey, N. J., assignor to Colgate-Palmolive-Peet Company, Jersey City, N. J., a corporation of Delaware

Application August 15, 1942, Serial No. 454,909

5 Claims. (Cl. 252—367)

The present invention relates to a method for converting molten anhydrous soap to a readily usable form and, more particularly, to a process for cooling and partially hydrating molten anhydrous soap, to an apparatus therefor, and to the product of said process.

Anhydrous soap has been made by various methods over a period of some years, and one of the problems raised has been to cool the molten soap without discoloring it by exposure to air. Numerous experimenters and investigators have advanced suggestions for solving this problem and for converting the molten soap into a usable form. According to one of these proposals, anhydrous soap is cooled and hydrated by discharging the molten soap into and beneath the surface of a pool of water or soap solution and intimately mixing the soap therewith, but this method provides a soap containing a large amount of water, part of which must frequently be removed, as when it is desired to make a milled soap. The removal of the water is a costly and time-consuming operation and requires equipment which occupies considerable space, all of which are disadvantageous. It has also been suggested to cool the soap out of contact with air by carrying it through a pipe by means of a worm conveyor, the solid anhydrous soap coming out as chips at the outlet end of the pipe. This method has the disadvantage that the solid anhydrous soap is extremely difficult to work and/or to dissolve, so that the soap is not in a readily usable form. Thus, although these and other suggestions and proposals have been made, no satisfactory method, so far as is known, has been provided for rapidly cooling molten anhydrous soap and converting it into a readily usable form.

It is an object of the present invention to provide a novel method for directly and rapidly cooling molten anhydrous soap out of contact with air without substantial change of shape and with or without partially hydrating the soap.

It is another object of the invention to provide a method for cooling and partially hydrating anhydrous soap in the form of threads and strings.

It is also an object of the invention to provide a novel apparatus for cooling anhydrous soap, with or without partially hydrating, while keeping the soap in a readily usable form.

The invention further proposes to provide filiform pieces of soap, either anhydrous or partially hydrated.

Other objects and advantages of this invention will be apparent from the following description,

taken in conjunction with the accompanying drawing, wherein:

Fig. 1 shows a longitudinal sectional view, partly diagrammatic, of an apparatus in accordance with the present invention;

Fig. 2 is a fragmentary detail section taken substantially on the line 2—2 of Fig. 1; and

Fig. 3 depicts a transverse section taken on the line 3—3 of Fig. 2.

According to this invention, molten anhydrous soap is expressed in the form of threads or strings out of contact with air into a pool of cooling liquid. The molten soap is cooled by contact with the liquid, and, when an aqueous body is employed as the cooling liquid, the outer portion of each string is partially hydrated. The strings are kept out of contact with each other for a short period of time, during which cooling is continued, and the filiform soap is then removed from the pool at a temperature where oxidation upon contact with air is substantially negligible and in a condition in which the soap can be passed directly to mills and plodders for further processing.

The molten anhydrous soap may be made by any of the methods known to the art. Thus, fats and fatty oils and/or free fatty acids and/or esters thereof may be mixed with alkaline agents in batch, intermittent or continuous operation, and the resulting reaction mixture heated to somewhat elevated temperatures and then flashed into a lower pressure zone to volatilize water or other solvents, glycerine (if any), alcohols (if any), and unsaponifiable matter and to recover the resulting anhydrous soap. In another method, the fatty material and alkaline agent are heated together in the absence of air and liquid water to a temperature above the melting point of the resulting anhydrous soap while passing a current of steam therethrough to remove glycerine, if any, and unsaponifiable matter. The alkaline or saponifying agents which may be used for saponifying these fatty materials include sodium and potassium hydroxides, carbonates, silicates, etc., lime, magnesium carbonate, pyridine, methyl morpholine, alkyl amines, alkanolamines, and other organic and inorganic bases and alkaline materials, and mixtures of these. The alkaline agent may be introduced in aqueous solution, in alcoholic solution, or in solutions of other solvents, or may be substantially anhydrous and/or substantially undiluted. It will be understood from the foregoing that molten anhydrous soap made by any other method would be equally applicable for treatment by the present

40

current of steam therethrough to remove glycerine, if any, and unsaponifiable matter. The alkaline or saponifying agents which may be used for saponifying these fatty materials include sodium and potassium hydroxides, carbonates, silicates, etc., lime, magnesium carbonate, pyridine, methyl morpholine, alkyl amines, alkanolamines, and other organic and inorganic bases and alkaline materials, and mixtures of these. The alkaline agent may be introduced in aqueous solution, in alcoholic solution, or in solutions of other solvents, or may be substantially anhydrous and/or substantially undiluted. It will be understood from the foregoing that molten anhydrous soap made by any other method would be equally applicable for treatment by the present

invention, and that this invention is not limited to any particular method or methods for preparing molten anhydrous soap.

After preparation by any desired process, the molten anhydrous soap is withdrawn from the reaction or separation vessel and is pumped through a plurality of orifices into and under the surface of a pool of cooling liquid. The soap may, if desired, be subjected to partial cooling by removal of part of its heat in any suitable heat exchange apparatus out of direct contact with a cooling fluid. Sufficient heat should be retained in the soap so that it is still fluid enough to be extruded through the orifices without clogging them.

The pool into which the molten anhydrous soap is expressed or extruded may be of water or other suitable liquid or may be an aqueous solution of soap, sodium chloride, sodium sulphate, sodium carbonate and/or other material capable of decreasing the solubility of the soap in the water. A non-solvent for soap, such as an alkane, cyclo-alkane, ether or halogenated alkane or ether, may similarly be employed as the cooling liquid. The orifices may be of any desired size and shape and may be uniform or not, as desired. In general, round orifices of about $\frac{1}{16}$ inch to about $\frac{1}{2}$ inch or larger are preferred, and $\frac{1}{4}$ inch orifices have been found to give satisfactory results. The orifices are preferably spaced apart by a distance of about twice to about ten times their own diameters to keep the strings of soap out of contact with each other for a short time.

Another method of keeping the strings apart is to surround each orifice with a short tube larger in diameter than the orifice and open at one end to the solution in the cooling vessel. The length of these tubes may be adjusted to keep the soap in individual strings for as long a time as is desired before allowing them to come into contact with each other, and such length will necessarily depend upon such factors as the temperatures of the soap and of the cooling liquid and the speed at which the soap is extruded, as will be apparent to those skilled in the art.

Since the difference in temperature between the molten anhydrous soap and the cooling liquid is necessarily great, the temperature difference normally being over 200° C., it is preferred to provide means for keeping the cooling liquid in motion. Such means may comprise stirrers and agitators in the cooling liquid, or, where practicable, it is preferred to flow the cooling fluid across the path of travel of the soap strings. Where tubes surrounding the orifices are employed, the tubes may be perforated to permit fresh cooling liquid to come into contact with the hot soap. This has the further advantage of sweeping away the vapor which is usually formed upon contact of the soap with the cooling fluid.

The process of the invention will now be described in connection with a novel apparatus for carrying the same into practice. Referring to the figures, reference character 1 designates a molten anhydrous soap supply vessel, the outlet of which is connected by means of a conduit with the inlet of a pump 2 driven by a motor 3. The outlet of the pump connects by means of a conduit with a heat exchange unit 4, and a pipe from this unit leads to a manifold or header 5 attached to the lower portion of the outside of a wall 6 of a cooling vessel 7. The wall 6 is perforated at its lower portion with a plurality of orifices 8, all of which are within the area covered by the manifold 5 upon the outside of the wall. A plurality of tubes

9 of diameter larger than the orifices 8 in the wall are perpendicularly affixed to the inner surface of said wall 6, the end of each tube surrounding one of the orifices, and each tube has a plurality of perforations 10. The other end of each tube is open in the cooling vessel 7. A continuous mesh conveyor 11 is provided in the vessel, said conveyor being at least as wide as the bank of tubes and being mounted in a position above said tubes and adapted to move material along the bottom of said conveyor in the same longitudinal direction as from the closed to the open ends of said tubes. A belt conveyor 12 of approximately the same width as the conveyor 11 and extending in substantially the same direction is mounted with its lower end beneath the forward end of the conveyor 11 and with its upper end outside the cooling vessel and said conveyor 12 is adapted to carry material upon the upper surface thereof. Means (not shown in the figures) are provided for driving the conveyors. A liquid inlet 13 is provided at the bottom 14 of the vessel 7 near a side thereof perpendicular to wall 6, and a pump is adapted to deliver cooling liquid to this inlet at a desired rate. An overflow outlet at the opposite side of the cooling vessel is provided for removal of the heated liquid. The overflow may be cooled, adjusted to proper composition with make-up water, solution, etc., and recirculated through the pump, if desired.

The operation of the device is relatively simple and will now be described in connection with the use of an aqueous body as the cooling liquid therein. Molten anhydrous soap is removed from the supply vessel 1 by the pump 2 and delivered to the heat exchange unit 4, where part of the heat in the soap is removed. Sufficient heat remains so that the soap in molten, semi-molten, plastic or semi-plastic form can be forced under pressure into the manifold 5 and through the orifices 8 in the wall 6 of the cooling vessel 7. The soap is expressed through the orifices 8 into the tubes 9. At the start of the operation, since the tubes are open at one end thereof to the aqueous cooling liquid in the vessel, the tubes are filled with the cooling liquid. When the hot anhydrous soap comes into contact with the aqueous liquid in the tubes, steam is formed, and an envelope of steam attaches itself to the strings of soap. The steam tends to make the soap rise in the cooling liquid, especially where a heavy brine solution is employed, and the strings of soap therefore rise to the upper parts of the tubes. The steam escapes through the perforations 10 in the upper sides of the tubes, and fresh cooling liquid comes into the tubes through the perforations at the lower sides. This permits fresh bodies of cool liquid to come into contact with the hot soap and increases the rate of cooling.

During the cooling operation, the outside of each soap string is hydrated, leaving a solid core of anhydrous soap within the string. Where the factors which influence the rate of cooling, as will be discussed infra, are such that the strings of soap are sufficiently cooled so that they will not conglomerate upon coming together, the strings emerge from the open end of the tubes 9 and are individually carried up by the steam envelope around them to the under-surface of the conveyor 11. They are carried along by the conveyor until the steam which surrounds them has escaped through the mesh of the conveyor into the upper portion of the cooling vessel, and the strings then fall upon the upper side of the con-

veyor 12. This second conveyor removes them from the vessel.

The number, size and spacing of the orifices in the wall of the cooling vessel, the length of the tubes provided, the speed at which the strings of soap move through the liquid, as well as the rate at which the cooling liquid is circulated through the vessel, the temperature of the cooling liquid, the amount of precooling of the hot anhydrous soap before extrusion through the orifices, the total length of time that the soap stays in the cooling vessel, etc., are among the factors which determine the form in which the soap is removed therefrom and the amount of hydration it possesses. These factors may be regulated to provide a soap in filamentous form which can be cut into short lengths and conveniently stored for subsequent processing, or the filiform soap may be fed directly to mills and plodders, there to have adjuvant materials incorporated therewith. Where the various factors are so adjusted that soap will conglomerate upon coming together to form a partially hydrated mass of soap, the amount of hydration can also be controlled to provide a soap which can be directly milled and plodded.

When it is desired to produce a substantially anhydrous product, a non-aqueous cooling liquid, preferably a high-boiling organic liquid in which the soap is substantially insoluble, may be employed, as aforesaid. The soap, after cooling, may be blown to volatilize the film of liquid thereon, especially if the liquid employed is relatively low-boiling, or such film may be removed by extraction with a low-boiling solvent for the liquid, which solvent may be removed from the soap in turn by blowing, slight heating or like methods. Thus, white oil, kerosene, decalin and/or tetralin may be used as the cooling liquid, and the residual film upon the filiform soap may be extracted with ethyl ether, petroleum ether and/or other volatile solvent.

Adjuvant materials which may be mixed with the soap include fatty acid soaps prepared by the same or other methods, resin acid soaps, naphthenic and alkylated naphthenic acid soaps, sulphated and sulphonated organic compounds, alkaline soap builders, water-soluble, water-softening acid compounds of phosphorus, and other salts including sodium carbonate, sodium silicates, trisodium phosphate, borax, sodium tetraphosphate, sodium bicarbonate, sodium sulphate, sodium chloride, sodium acetate, sodium hypochlorite, sodium thiosulphate, sodium perborate, sodium tartrate, sodium citrate and sodium oxalate, and the corresponding ammonium, substituted ammonium and potassium salts of the corresponding acids; insecticidal, germicidal, styptic and medicinal agents, including aluminum chloride, mercuric chloride and various copper and lead salts; coloring agents, abrasives, fillers, and water-dispersible gums, including dyes, lakes, pigments, silica, kieselguhr, silica gel, feldspar, precipitated chalk, pumice, infusorial earth, bentonite, talc, starch, Irish moss, sugar, methyl cellulose, agar, gum tragacanth, gum arabic, and polyvinyl alcohol; liquids, such as ethyl alcohol, glycerol, cyclohexanol, naphtha, benzene, kerosene, turpentine, pine oil, decalin and tetralin and the like. The type of addition agent will depend upon the ultimate use of the new composition. Other ways of incorporating these addition agents besides mixing the final product therewith are to admix the adjuvant materials with the raw fatty material and/or the saponifying agents

before flashing or heating or by simultaneously flashing a second solution containing such adjuvant materials.

The present process has the advantage of 5 cooling anhydrous soap out of contact with air so that decomposition and discoloration of the product are avoided, while simultaneously hydrating the soap to a desired amount suitable for processing without having to remove part 10 of the water. A further advantage of the process is to provide soap in a convenient and easily handled form, which may be easily dissolved or which may be used directly in mills and plodders in the manufacture of a milled soap.

15 It will be understood that the term "molten" as applied herein to the anhydrous soap treated is also intended to include said soap in semi-molten, plastic, and semi-plastic forms.

Although the present invention has been described in connection with a particular embodiment, it will be understood by those skilled in the art that other variations and modifications of the invention can be made and that various equivalents can be substituted therefor without 20 departing from the principles disclosed herein. Thus, instead of introducing the molten soap at the side of the pool of cooling liquid, the orifices may be positioned at either the top or the bottom of the pool, depending upon the gravity and 25 boiling point of the liquid used and whether the strings of soap will at first tend to fall or to rise upon being extruded into the cooling liquid. Such arrangement may suffice in some cases to 30 keep the strings separated from each other until cool. It will also be appreciated that, although 35 the extruded soap has been described as in filamentous form, the orifices may be of such shape and dimensions that ribbons, sheets, and the like can be produced. These and other variations and modifications are believed to be within 40 the scope of the present specification and within the purview of the appended claims.

I claim:

1. A process of treating molten anhydrous soap 45 which comprises extruding molten anhydrous soap through a plurality of orifices into a body of an aqueous cooling liquid, maintaining the strings of soap so formed out of contact with each other for a time interval sufficient for cooling said 50 strings below the temperatures of substantial conglomeration and of substantial oxidation in the presence of air and insufficient for substantially changing the shape of the soap and for 55 more than partially hydrating said soap, and removing said strings from said body of liquid.

2. A process of treating molten anhydrous soap which comprises extruding molten anhydrous soap out of contact with an oxidizing medium through a plurality of orifices into and below the surface of a body of an aqueous cooling liquid, maintaining said soap extrusions therein out of contact with each other until partially hydrated and cooled below the temperature of substantial conglomeration, and removing said partially hydrated soap from said liquid body without substantial change in shape.

3. A process of treating molten anhydrous soap which comprises passing continuous strings of molten anhydrous soap through a body of an aqueous cooling liquid, maintaining said strings therein out of contact with each other until partially hydrated and cooled below the temperature of substantial conglomeration, continuously removing said partially hydrated soap in filamentous form.

tous form from said liquid body, and milling and plodding said filiform soap.

4. A process of treating molten anhydrous soap which comprises extruding molten anhydrous soap out of contact with an oxidizing medium through a plurality of orifices into and below the surface of a body of a high-boiling organic liquid wherein the soap is substantially insoluble, maintaining said soap extrusions therein out of contact with each other until cooled below the temperature of substantial conglomeration, removing said soap from said organic liquid body without substantial change in shape, washing said soap with a volatile organic solvent wherein residual

high-boiling organic liquid upon said soap is soluble and wherein the soap is substantially insoluble, and vaporizing residual volatile solvent from said soap.

5. A process of treating molten anhydrous soap which comprises extruding the molten anhydrous soap through a plurality of orifices into a body of a cooling liquid, maintaining the strings of soap so formed out of contact with each other for a time sufficient for cooling said strings below the temperature of substantial conglomeration, and removing said cooled soap from said body of liquid.

JOHN ROSS.
